UNITED STATES PATENT OFFICE.

WILLIAM DOVE, OF NEW YORK, N. Y., AND WILLIAM ALLAN LA SOR, OF RAHWAY, NEW JERSEY.

PRINTER'S PLATE-BLOCK.

SPECIFICATION forming part of Letters Patent No. 776,502, dated December 6, 1904.

Application filed February 19, 1904. Serial No. 194,313. (No model.)

To all whom it may concern:

Be it known that we, WILLIAM DOVE, of the city, county, and State of New York, and WILLIAM ALLAN LA SOR, of Rahway, Union county, State of New Jersey, citizens of the United States, have invented certain new and useful Improvements in Printers' Plate-Blocks, of which the following is a specification sufficient to enable others skilled in the art to which the invention appertains to make and use the same.

Our improvements relate to blocks for holding stereo or other plates to be printed from while on the form.

15 The main object of our invention is to facilitate the adjustment of a plate with accuracy upon the block and insure its perfect alignment thereon.

Our invention consists, primarily, in the use 20 upon one side of the block of means for gagging the plate accurately and simultaneously at least two points in any given line within certain limits parallel to the side of the block, the plurality of gages being controlled and 25 actuated in unison by a single forwarding and retracting device.

Secondarily, our invention includes certain 30 features in the construction, combination, and arrangement of parts hereinafter described and claimed specifically.

In the accompanying drawings, Figure 1 is 35 a top view of our improved block; Fig. 2, a view of the under side thereof; Fig. 3, an edge view; Fig. 4, a longitudinal section upon plane of line 4 4, Fig. 1; Fig. 5, a transverse section upon plane of line 5 5, Fig. 1. Fig. 6 is a top view illustrating the use of our gages. Fig. 7 is a similar view showing a plate secured in position. Fig. 8 is a longitudinal section upon plane of line 8 8, Fig. 1; Fig. 9, a transverse section upon plane of line 9 9, Fig. 1; and Fig. 10, a partial top view showing a modification.

B is the block as a whole, the upper surface 45 of which is formed with the gage-lines b b', parallel, respectively, to one longitudinal side and one end of the block.

a a a are three plate-clamps of usual con-

struction actuated by rotatable screws in a manner well known in the art. 50

G G are two gages coupled together in a line parallel to the side of the block and moved simultaneously by means of a common controlling-plate C. The edges g g of the gages above the surface of the block are beveled to overlap the plate P, so that they perform the double function of clamps and gages. These gages G G may be simultaneously advanced and retracted by various well-known mechanical expedients, and we do not limit ourselves to the identical form and construction of parts shown in this respect, the essential feature of the invention being the combination, with a plurality of gages arranged in a line parallel to the side of the block, of means 60 for advancing and retracting said gages in unison and simultaneously toward and from the center of the block.

In the construction shown in the drawings the gages G G travel in transverse slots b b' 70 in the block B and also engage with inclined parallel slots c c in the controlling-plate C, which latter is mounted upon the under side of the block and is movable longitudinally thereon by suitable means, as by the pinion 75 e, engaging with the rack c', formed in the edge of the controller-plate, the pinion being actuated from the top of the plate by means of a screw-driver or like implement through the medium of the nicked upper end of the 80 pinion or arbor e', as will be understood by reference to Figs. 1 and 8.

Automatic means are provided for locking the controlling-plate C against accidental movement, as by a spring-pawl f, engaging 85 either the teeth of the pinion e or of the rack c'.

It is obvious that the upper or clamping edges g g of the gages G G may be united to form a single straight edge or bar, as indicated in Fig. 10, if desired, without departing from the spirit and intent of our invention in this respect, which contemplates the setting or gaging of a line parallel to the edge of the block simultaneously at a plurality of 90 points along said parallel line by the use of a 95

plurality of gages, whether united above the block by a common straight edge or other connections or independent of each other, as in the other figures of the drawings. The result is the same in either case. The parallel line is quickly and accurately set by a single operation through the medium of the controller-plate C. The true alinement of the plate P being thus established, it is a comparatively simple matter to secure the plate P in position by means of the ordinary clamps *a a a*, the end gage G' having first been set to determine the position of the plate longitudinally upon the block.

15 The end gage G' is preferably secured directly to a second controller-plate C', mounted on the under side of the block B, the body of the gage projecting through the longitudinal slot *b*³ and being provided with the beveled edge *g'* for engagement with the plate. This second controller-plate C' may be operated by a pinion and rack similar to the first-named controller-plate C or by any other mechanical expedient, and it is also locked automatically 25 in position by a spring-pawl or equivalent.

What we claim as our invention, and desire to secure by Letters Patent, is—

1. The combination with a printer's plate-block, of a plurality of gages arranged in a line parallel to one edge of the block and connected and controlled in unison by a common forwarding and retracting device, said forwarding and retracting device comprising a controlling-plate with parallel inclined slots

in which said gages engage, and means acting 35 directly on said plate, and means for automatically locking the said parts in position against accidental movement.

2. The combination with a printer's plate-block, of a plurality of gages arranged in a line parallel to one longitudinal edge of the block, and connected and controlled in unison by a common forwarding and retracting device comprising a controlling-plate with parallel inclined slots in which said gages engage 45 and means acting directly on said plate, means for automatically locking the said parts in position, a gage parallel to one end edge of the block, means for advancing and retracting the same and automatic means for holding 50 the same against accidental movement.

3. The combination with a printer's plate-block, having parallel slots at one edge, of a controlling-plate movably mounted in said block below its upper surface and having parallel inclined slots intersecting the slots of the block, said plate having a rack formed upon one edge, means mounted in the under side of the block to engage and operate said rack and plate, and gages engaged in the slots 60 of the block and plate and having beveled clamping edges extended above the block, as and for the purpose specified.

WILLIAM DOVE.
